(57) CLAIM

The ornamental design for a waffle maker, as shown and described.

DESCRIPTION

FIG. 1 is a front perspective view of a waffle maker showing my new design;

FIG. 2 is a top plan view thereof;

FIG. 3 is a front view thereof;

FIG. 4 is a right side view thereof; and,

FIG. 5 is a back view thereof.

The broken lines shown in the drawings are for illustrative purposes only and form no part of the claimed design.
